Primary Examiner — Clint A Samuel(74) *Attorney, Agent, or Firm* — ROTHWELL, FIGG, ERNST & MANBECK, P.C.(57) **CLAIM**

The ornamental design for a lamp as shown and described.

DESCRIPTION

FIG. 1 shows a top perspective view of the lamp in a first configuration.

FIG. 2 shows a left side view thereof in an alternate configuration.

FIG. 3 shows a front view thereof in the alternate configuration.

FIG. 4 shows a right side view thereof in the alternate configuration.

FIG. 5 shows a top view thereof in the alternate configuration.

FIG. 6 shows a bottom view thereof in the alternate configuration; and,

FIG. 7 shows a back view thereof in the alternate configuration.

The broken lines shown in the figures depict portions of the lamp that form no part of the claimed design.

1 Claim, 7 Drawing Sheets(56)
